UNITED STATES PATENT OFFICE.

JOHN B. PLANT, OF PHILADELPHIA, PENNSYLVANIA.

DESIGN FOR A SHOE-SOLE.

SPECIFICATION forming part of Design No. 25,594, dated June 2, 1896.

Application filed March 25, 1896. Serial No. 584,885. Term of patent 7 years.

To all whom it may concern:

Be it known that I, JOHN B. PLANT, a citizen of the United States, residing at Philadelphia, in the county of Philadelphia and State of Pennsylvania, have invented and produced a new and original Design for Shoe-Soles, of which the following is a specification, reference being had to the accompanying drawings, showing a part thereof.

10 Figure 1 is a bottom plan view of a sole, showing my design; and Fig. 2, a longitudinal central section thereof.

The leading feature of my design consists of a sole and heel formed together, with cross-wise corrugations A, broken by V-shaped notches II, said corrugations being inclosed by a bead E, composed of compound curves following the outline of the sole. A ledge D is formed a short distance from the bead with 20 an intervening semicircular groove E. The outer ledge is slightly extended at F to give the general effect of a bevel. This extended portion merges with the rectangular edge which surrounds the heel. Extending around 25 these corrugations is a bead C, composed of compound curves which follow the general

outline of the shoe-sole. Running parallel with the bead C, at a short distance therefrom, is a ledge D of approximately semicircular cross-section, and a space between this 30 ledge and the bead C forms a semicircular groove E. The outer edge of the ledge is slightly extended at F, so as to give the general effect of a bevel, with the exception of that part of said ledge which extends around the 35 heel, at which point it is rectangular.

The shank of the sole between the bead C presents a plain surface G. The corrugations are broken by V-shaped notches II, which are arranged in the same general direction as the 40 contour of the sole, thus presenting to the eye a checkered appearance.

What I claim as new and useful is—
The design for a shoe-sole substantially as shown and described. 45

In testimony whereof I have hereunto affixed my signature in the presence of two subscribing witnesses.

JOHN B. PLANT.
